UNITED STATES PATENT OFFICE.

CARL G. OLSON, OF CHICAGO, ILLINOIS, ASSIGNOR TO ILLINOIS TOOL WORKS, OF CHICAGO, ILLINOIS, A CORPORATION OF ILLINOIS.

HOB GRINDER.

Application filed February 5, 1926. Serial No. 86,206.

My invention relates to hob grinding machines and the object of the invention is to facilitate changing the grinding wheel from one side of the hob teeth to the other.

Ordinarily hob teeth have sloping sides to conform with the selected pressure angle, and owing to this and the fact that the teeth are arranged in the form of a helix, the matter of changing the grinder from one side of the teeth to the opposite side involves adjustment which is somewhat complex. In the case of straight gashed hobs still another factor must be taken into consideration, due to the fact that the body of the tooth is not at right angles to the gash. My purpose is to provide means whereby the necessary changes and adjustments may be taken care of in a simple and reliable manner.

I accomplish my object by the mechanism illustrated in the accompanying drawings.

Figure 1 is an assembly view of the principal parts concerned with my invention. Some of the parts are shown in vertical axial section in order to better reveal the construction.

Figure 2 is a rear elevation of parts of the machine shown in Figure 1. This view shows the grinder head and parts immediately supporting it and in dotted lines indicates an alternate position which the grinder head may occupy for grinding a hob of the opposite lead or "hand". In other words this figure illustrates the change from a right to a left hand hob.

Figure 3 is a plan view of the grinder head and its support. This figure also shows the hob and a portion of the hob spindle.

Figure 4 is a sectional elevation on the line 4-4 Figure 3.

Figure 5 is a sectional elevation on the line 5-5 Fig. 4.

Figure 6 is a perspective view of the grinder head, adjusting shim, tool rest and anchor bolt, the parts being separated to show their construction and to indicate their relationship in the assembled machine.

Figure 7 is diagrammatic view illustrating the reasons for changing the elevation of the grinder in changing from one side of the hob teeth to the other when treating a straight gash hob. This adjustment may for convenience be termed the vertical shift.

Figure 8 is also diagrammatic and shows on a larger scale the reasons for making the vertical shift or adjustment.

Figure 9 is a detail view partially diagrammatic showing the relation of the grinding wheel to the hob in the different positions.

Like numerals denote like parts through out the several views.

The hob 1 is supported upon the hob spindle 2. In Figures 1, 3 and 4 a spiral gash hob is illustrated while in the diagram Figures 7 and 8 a straight gashed hob is illustrated. The hob spindle has a rotary movement about its own axis and also a longitudinal or axial movement lengthwise of its axis and also a radial movement for moving the hob bodily toward and from the grinding wheel in conformity with the relief of the hob teeth. These movements may be accomplished in different ways without exceeding the scope of my invention. In the illustrated case the mechanism for producing these movements of the hob is like the one shown in my earlier Patent No. 1,575,713. It will be sufficient for the present purpose to say that the hob spindle is journaled in two bearings 4, 7 mounted in a frame 6 which is in the form of a housing closed by a cover 8. The journal 6 is internally threaded and constitutes a lead nut in which works the threaded end portion 10 of the hob spindle. This forms the lead screw for moving the hob axially in conformity with the thread angle or helical lead of the hob.

The housing 7 rocks or rolls upon its support, for moving the hob bodily toward and from the grinder in accordance with the relief in the hob teeth. One part 12 of the support is shown in Figure 1 and a steel tape 14 is inserted between the housing and its support for holding the housing in position as explained in my aforesaid patent.

The hob spindle is rotated by a gear 16 which is fastened to it and meshes with wide face driving pinion 18. This is driven by suitable gearing including a pinion 20. The pitch circle of pinion 18 is tangent to the plane of the support 12.

Now referring to the grinder and its support: A tool carriage 22 slides upon a guide 24 arranged crosswise of the hob spindle. It is controlled by a feed screw 26. A cross carriage 28 is slidably mounted on the carriage 22 and is controlled by an adjusting screw 30. A tool rest or base 32 is supported on carriage 28. It pivots about a pin 34 and has arcuate slots 36 for receiving clamping

screws 38 by which the tool rest may be held in the proper angular adjustment. This determines the angle of obliquity between the hob spindle and the grinder spindle herein-after described.

Above the tool rest is a grinder head and this comprises a block shaped shank 40 and a sleeve 42 which forms an extension or bracket from it, and holds a "quill" 44. The 10 spindle 46, which supports the grinder wheel 48, is journaled in the quill and driven by a sheave 50 and belt 52. For clearance and other reasons the sleeve 42 and grinder spindle axis are arranged at an angle to the hob 15 spindle axis when the shank block is at right angles to it as shown in Figure 3. In the form shown the top and bottom surfaces of the shank block 40 are parallel.

The quill is slidable longitudinally in a 20 sleeve and is held in adjusted position by a set screw 54.

The shank 40 rests ordinarily upon a wedge block 56 shown separately in perspective in Figure 6. This block rests upon 25 the top of the tool rest 32 and has a central aperture 58 for accommodating an anchor bolt 60 by which the parts may be clamped together. At the lower end the anchor bolt or clamping screw 60 is suitably fastened to 30 the support 32 by means of a pin 62 as best shown in Figures 4 and 5. The shank 40 is centrally apertured to accommodate the bolt and is held down by a nut 64 screwing on the upper end of the bolt.

The wedge block has a slot 66 at each end for engaging locating pins 68 projecting upward from the tool rest 32. These pins prevent the wedge block from shifting in any direction upon the surface of the tool rest. 40 Channels 70 are formed in the upper and lower surfaces of the shank 40 and these fit over the rounded upper ends of the locating pins. The construction is such that the grinder head may change its angular position upon the top of the tool rest in accordance with the shape of the wedge block but will be held by the pins against shifting in a direction transverse to channels 70. These 45 channels extend transversely to the hob spindle and permit the grinder to be adjusted 50 radially toward and from the hob.

In practice, the parts are assembled as shown in Figures 1 to 5 inclusive. It will be observed that the axis of the conical grinding wheel lies at an oblique angle to a vertical plane passing through the hob axis and also to a horizontal plane passing through the hob axis. With a given shaped grinding wheel the first angle varies in accordance with the pressure angle of the teeth and the second angle varies with the helix angle of the hob. In preparing for grinding the parts are so adjusted that the median line of the shank of the grinder head will 55 pass through the center of the space between

the two lines of contact of the grinder on the hob teeth. In other words, when the grinder acts upon a tooth and when acting upon the tooth on the opposite side of said space will make line contact with the latter tooth 70 and the grinding machine will be so adjusted that the median line of the grinder head shank will lie half way between these two lines. The advantage is that when the grinder head is turned over to act upon the opposite side of the hob teeth it will not be necessary to make an adjustment of either 75 the hob or the grinding wheel in a direction lengthwise of the hob. This principle is illustrated diagrammatically in Figure 9 80 wherein M represents the median line. It is the same as the upper portion of the line 4-4 in Figure 3.

When one side of the hob teeth have been ground the grinder head is lifted off and turned over so that it will be reversed from the position shown in full lines in Figure 9 to the position shown in dotted lines in said figure. This is accomplished by first removing the nut 64 from the anchor bolt 60, then lifting off the grinder head and turning it over and then securing the parts in the new position by reapplying the nut 64. In the case of the smaller single thread hobs this reversing of the grinder head is made without disturbing the wedge block and while this imparts a slight discrepancy theretofore the inaccuracy is so small as a practical matter that it is negligible. In the case of hobs of larger sizes or larger helix angles 100 and in hobs of double thread another factor must be taken into consideration. This will be understood by reference to the diagrams, Figures 7 and 8, which show a straight gash hob. An adjustment must be made which 105 will cause the grinder to commence its work at the front of the hob tooth when the grinder is reversed. In the diagram the line F-F represents the front of the teeth facing any given gash. The line A-A represents 110 a normal to the line of contact when the grinder is on one side of the space, and the line B-B represents a normal to the line of contact when the grinder is on the other side of the space. If we assume that the line 115 F-F lies in a horizontal plane it is evident that if the grinder is at first located at the elevation indicated by the center of the full line circle C' it must, when reversed, be lowered to the extent indicated by the center of 120 the dotted line circle C'. For the sake of explanation this lowering may be referred to as the "vertical shift," although it will be understood that the term "vertical" is employed because in the illustrated embodiment 125 of the invention the shift would be vertical. To express the principle universally it would be more accurate to say that there is a relative adjustment represented by a narrow angle centered at the hob axis and lying in 130

- a plane perpendicular to the axis of the hob. In my machine this "vertical shift" is accomplished in a very simple and effective manner, and that is by substituting a thinner wedge block when the grinder head is reversed. By employing this expedient the grinder head will automatically come both to the correct angles and to the correct elevation and will cause the grinder to make the necessary horizontal shift (lengthwise of the hob) without requiring any other manipulation of the machine on the part of the operator. Thus in my machine, in grinding straight gash hobs, by merely turning the grinder head over and substituting a wedge block of different thickness the line of contact of the grinder will be shifted both vertically and horizontally and the grinder will be brought to the position required by the pressure angle and by the helix angle of the hob.
- Having thus described my invention what I claim as new and desire to secure by Letters Patent is:
1. A hob grinding machine having a hob spindle, a grinder spindle, a base frame, means for causing relative movement between the base frame and the hob spindle in a direction parallel to the hob spindle, a grinder spindle frame for holding the grinder spindle at an oblique angle to the hob axis, and removable means insertible between the base frame and the grinder spindle frame for holding the latter at an angle with the hob spindle corresponding with the helix angle of the hob.
2. A hob grinder having a hob spindle, a grinder spindle, a base frame, means for causing relative movement between the base frame and the hob spindle in a direction parallel to the hob spindle, a grinder head for holding the grinder spindle, said grinder head being reversible, top for bottom, and separate means cooperating with the grinder head and base frame for supporting the grinder head in either of two positions for grinding opposite sides of the hob teeth and automatically compensating for the helix angle of the hob and the axial spacing of the surfaces to be ground.
3. A hob grinder having a hob spindle, a grinder head, a support for the grinder head, and a removable plate insertible between the support and with the grinder head for holding the grinder head at a specific angle, depending upon the shape of the detachable element.
4. A hob grinder having a hob spindle, a grinder head, a support for the grinder head, and a removable wedge plate located between the support and the grinder head whereby the grinder head may be held at different angles by substituting plates of different form.
5. A hob grinder having a hob spindle, a

grinder head provided with a block shaped shank, a tool rest, and means on the tool rest and located beneath the shank block for holding the latter and the grinder spindle at the proper angle to correspond with the helical lead of the hob, the shank block having parallel top and bottom surfaces.

6. A hob grinder having a hob spindle, a grinder head provided with a block shaped shank whose top and bottom surfaces are parallel, a tool rest, and an angular block inserted between the shank block and the tool rest for holding the grinder spindle in proper position with respect to the helix angle of the hob.

7. A hob grinder having a hob spindle, a grinder head provided with a block shaped shank whose top and bottom surfaces are parallel, a tool rest, an angular block inserted between the block shaped shank and the tool rest for bringing the grinder into proper contactual relation with the hob teeth in accordance with the helix angle of the hob, and screw clamp mechanism for clamping the block shaped shank to the tool rest at the angle determined by the shape of the angular block.

8. A hob grinder having a hob spindle, a grinder spindle, means for causing relative travel of said spindles in a direction parallel to the axis of the hob, a grinder head reversible top for bottom for holding the grinder spindle in predetermined position relatively to the hob spindle axis in accordance with the slope of the sides of the hob teeth, and compensating means for holding the grinder head in either of two positions, said compensating means holding the grinder at different levels when in different positions to thereby maintain symmetrical grinding contacts on opposite sides of the hob teeth.

9. A hob grinder having a hob spindle, a grinder head having a block shaped shank having parallel top and bottom surfaces, a tool rest, a removable block on which the shank of the grinder head seats, said block seating upon the tool rest, and locating keys rigidly held in one of the parts and fitting into the other part for positioning the shank of the grinder head on the tool rest, said keys passing through the removable block for holding the latter in position also.

10. A hob grinding machine having a hob spindle, a grinder head, a support for the grinder head, and removable substitute blocks of different thicknesses to hold the grinder head at different elevations for grinding on different sides of the hob teeth.

11. A hob grinder having a hob spindle, a grinder head, means for causing relative movement between the hob spindle and grinder head for relieving the work, a grinding wheel rotatably mounted in the grinder head with the axis at an oblique angle to

- the axis of the hob, and substitute spacer blocks insertible between the grinder shank and the tool rest for holding the grinder wheel in proper position with respect to the 60
6 helix angle of the hob, said spacer blocks being of different thicknesses to hold the grinder wheel at different elevations when the wheel is in contact with different sides of the hob teeth.
- 10 12. A hob grinder having a hob spindle, a grinder head, means for causing relative movement between the hob spindle and the grinder head for relieving the work, a grinding wheel rotatably mounted in the grinder 65
15 head with the axis at an oblique angle to the axis of the hob in conformity with the pressure angle of the hob, and supporting means for the grinder head capable of definitely holding the grinder head in two positions one hundred and eighty degrees apart 70
20 for grinding opposite sides of the hob teeth and adapted to automatically maintain the same level at the point of contact of the grinder wheel with the hob when the grinder 75
25 head is changed from one position to another.
13. A hob grinder having a hob spindle, a grinder head, means for causing relative movement between the hob spindle and the 80
30 grinder head for relieving the work, a grinding wheel rotatably mounted in the grinder head with its axis at an oblique angle to the axis of the hob in conformity with the pressure angle of the hob, and supporting means for the grinder head capable of holding the grinder head in two positions one upside down with respect to the 85
35 other for grinding opposite sides of the hob teeth and adapted to automatically adjust the grinder head both in a direction parallel 90
40 to the axis of the work and in a direction perpendicular to a plane containing the axis of the work and the point of application of the grinder to the work when the grinder 95
45 head is changed from one position to another.
14. A hob grinder having a hob spindle, a grinder head, means for causing relative movement between the hob spindle and the 100
50 grinder head for relieving the work, a grinding wheel rotatably mounted in the grinder head with its axis at an oblique axis angle to the axis of the hob in conformity with the pressure angle of the hob, the grinder 105
55 head having a reversible block shaped shank having parallel top and bottom surfaces, a
- support for said shank, and interfitting means between the support and the shank, the interfitting portion on the block being in such position that when the shank is reversed, top for bottom, the grinder wheel will be adjusted axially of the hob to contact the opposite side of the hob tooth.
15. A hob grinding machine having a grinder head which may be reversed by being turned over, said grinder head when centralized, opposite to the middle of a tooth space, holding the grinder in position to make line contact with a tooth on one side of said space and holding the grinder spindle at an angle corresponding to the pressure and helix angles of the hob teeth, a support therefor, and two wedge blocks of different thickness for insertion between them in different positions of the grinder 70
75 head, whereby when the grinder head is merely turned over and the alternate block positioned, the grinder will be at changed elevation, and the grinder will make line contact with the tooth on the opposite side of the space and the grinder spindle axis will be at the corresponding pressure and helix angles.
16. In a machine for grinding hobs and like threaded objects, a work spindle, a 85
80 grinder head, and a base on which the grinder head is supported, the grinder head being reversible top for bottom, whereby the grinder may be turned over for grinding the opposite sides of the thread of the work, said base holding the grinder head tilted at an angle corresponding to the helix angle of the thread of the work.
17. In a machine for grinding hobs and like threaded objects, a work spindle, a 85
85 grinder head, and a base on which the grinder head is supported, the grinder head being reversible top for bottom, whereby the grinder may be turned over for grinding opposite sides of the thread of the work, said base holding the grinder head tilted at an 90
95 angle corresponding to the helix angle of the thread of the work, the base being formed in a plurality of parts one of which is a removable plate, whereby by employing plates of different form the grinder head 100
105 may be held tilted at different angles and different elevations.

In witness whereof, I have hereunto subscribed my name,

CARL G. OLSON.
